In Germany March 17, 1927

4 Claims. (Cl. 250—33)

It has been found in practice that in the case of short-wave work it is suitable to radiate the energy from a plurality of wires arranged a certain distance apart rather than from a single antenna wire, it being immaterial so far as the present invention is concerned in what particular way these aerials are geometrically disposed. However, all systems comprising a plurality of aerials have this feature in common that the constituent antenna are equivalent with reference to one another, and that they must be identically coupled with the transmitter. The coupling is effected by means of energy (feeder) wires, and these, of course, must be branched when several antennæ are employed.

In order that the energy of the transmitter may be totally transmitted to the different aerials, it is necessary that the energy lines should be coupled with one another and with the respective antennæ in a way free from reflection. The same situation holds true if a receiver is to be coupled with a plurality of aerials. In other words, at each branching point of the energy line, say, at the junction or transition point from 1 to n wires, the natural impedance of all of these n wires must be equal to that of the main line, in other words, each individual line must possess the n -fold resistance of the main line. If each of these n many lines again divides into a number of others, the same condition holds true for such new branch point. Finally, however, also the useful, that is, the antenna resistance must be adapted to the energy line.

It has already been known from low-frequency problems, for instance, from ordinary telephone lines that the natural impedance of the main energy line may be adapted to that of the branch lines by the aid of transformers having conveniently chosen transformation ratios. But the question of dimensioning and disposing the lines was mainly solved from a viewpoint of insuring minimum cost of installation, indeed, such lack in agreement between the wave resistance as resulted from such policy and plan was corrected by the convenient selection of the transformation ratios of coupling transformers.

Now, in the case of radio frequency work, especially with ultra-short waves, transformers, most preferably of the air-core type, could be employed for the said purpose. However, these involve the disadvantage that they establish coupling not in a purely inductive manner, but also capacitively, so that as a consequence the phase relations between the primary and the secondary become uncertain. When the question of proper

phase relationship is important (and this is the case of transmitting and receiving with a great number of antennæ which are to bear well-defined phase relations with one another by being arranged at certain distances), it is a better plan not to use such uncertain transformer coupling and to couple the energy lines at the junction points directly with one another.

According to the disclosures of the present invention, while dispensing with the said coupling transformers by establishing direct connection between the input and output wires at the junction points, wave reflection is completely precluded by that the necessary conditions and relations as regards natural impedance are insured simply by the convenient selection of the line constants for the main and branch lines. The factors governing the line or wire constants are the cross-sections and the geometrical form of arrangement of the "wire paths", the distances between the wires, and the dielectric surrounding the wire paths.

Choosing for the line material metals of high conducting powers, then it can be supposed that the speed of propagation of the energy is very closely equal to the speed of light. In this case, the natural impedance depends essentially upon the mutual capacitance of the "path" of the line per unit length of wire or line. If the capacity is high, then the natural impedance will be low, and vice versa. The capacity between the line paths, at the same distance between the conductors, becomes higher whenever the geometrical size of the line path, for instance, in the case of wires, the cross-section is increased. Hence, by enlarging the cross-section, the natural impedance can be diminished. A reduction in the distance between conductors, or an increase in the dielectric constant of the medium surrounding the line, would have the same effect. For the supply of antennæ according to the present invention, the following forms of line paths may be considered:

(a) Concentric tubes whose diameters are changed at each branch point in accordance with whatever change in natural impedance may be desired.

(b) Parallel wires or tubes whose mutual distance or whose cross-sections are varied at each branching point.

(c) Parallel wires or tubes which are screened towards the outside by a common sheath or envelope. In this case, there is a further chance to utilize the influence of the envelope upon the line capacity for insuring the desired natural

impedance, for instance, by varying the distance between the envelope and the lines.

- (d) Lines consisting of several paths, parallel from both an electrical as well as spatial view-point with or without external screening or shielding by external envelopes. In this case, there is an additional chance to vary the natural impedance at the branching points by that the number of paralleled conductors may be altered.
- 10 All of the arrangements hereinbefore mentioned may be embedded in insulation materials possessing well defined dielectric constants, the value of the dielectric constant being taken into consideration in choosing the dimensions of
- 15 the different conductor parts.

As regards the last conductor section directly preceding the antenna, its natural impedance must suitably be so chosen that it will come as closely as possible to the antenna resistance. The 20 coupling between the energy line and the antenna is then to be chosen of the simplest possible form.

The following practical example furnishes numerical values for an energy line to be dimensioned according to the present invention and as 25 shown in the accompanying drawings.

The problem to be solved is to establish coupling between a transmitter S and four identical antennae A, the latter to be excited at the same phase. Suppose the resistance of each aerial is 30 $R_a=120$ ohms. Each antenna is to be coupled with the respective energy supply line directly without the insertion of a transformer.

According to the present invention, this is effected by that the transmitter first works upon 35 a main supply line having a natural impedance $Z_1=30$ ohms. This main line may consist of two concentric tubes, the outer tube having a diameter of 100 mm, and the inner tube a diameter of 60 mm. This main line is divided or branched into 40 two sub-lines or secondary lines each of a natural impedance of $Z_2=60$ ohms so that combinedly they result again in 30 ohms. Also in this case, concentric tubes may be used, the outer one of a diameter of 100 mm, and the inner one of 35 mm. The said two secondary lines are again 45 branched each into two energy lines (consisting again, for instance, of concentric tubes, the outer one of 100 mm, and the inner conductor of 12.5 mm. diameter). These last-named conductors 50 have a natural impedance each of $Z_3=120$ ohms, so that they can be coupled directly with the antenna in a way affording freedom from reflection.

Having thus described our invention what we 55 desire to protect by Letters Patent is as follows:

1. An antenna system having, in combination,

a plurality of pairs of spaced aerials, a transmission line of known impedance coupled to high frequency apparatus, said transmission line comprising concentric conductors of known mutual capacity, direct connections between each antenna in each pair and an antenna in another pair, and a plurality of branch lines directly included in said connections and directly connecting said connections to the transmission line, said branch lines comprising concentric conductors of less mutual capacity than said transmission line and each having an overall impedance greater than the impedance of the transmission line.

2. An antenna system having, in combination, 90 a plurality of pairs of spaced aerials, a transmission line of known impedance coupled to high frequency apparatus, direct connections extending between each antenna in each pair and an antenna in another pair, said direct connections including a plurality of branch lines directly connected to the transmission line, said branch lines each having an overall impedance greater than the impedance of the transmission line, said transmission line and branch lines comprising 95 spaced conductors, the spacing between the branch line conductors being greater than the spacing between the transmission line conductors.

3. A system for directly coupling a plurality of spaced aerials to a transmission line of known 105 impedance comprising a plurality of branch lines directly connected to said aerials and connected to said transmission line, each of said branch lines having an overall impedance approximately equal to the impedance of the transmission line 110 multiplied by the number of branches, said transmission line comprising two concentric tubes of predetermined diameter and said branch lines including tubes having diameters different from said branch lines.

4. An antenna system having, in combination, a two wire transmission line connected to high frequency apparatus, two pairs of antennæ, individual ground connections at each of said antennæ of said pairs, a direct connection between an antenna in each pair to the ground of the other antenna in the same pair, and a plurality of branch lines directly connected to said antenna connections and to said two wire transmission line, said branch lines taken alone each having 120 an overall impedance greater than the impedance of said transmission line, but less than the overall impedance of said antenna connections taken alone.
